UNITED STATES PATENT OFFICE

154,732

DESIGN FOR A HEAD FOR CANES AND SIMILAR ARTICLES

William D. Adams, Tampa, Fla.

Application June 28, 1948, Serial No. 147,250

Term of patent 7 years

(Cl. D88—4)

To all whom it may concern:

Be it known that I, William D. Adams, a citizen of the United States, residing at Tampa, in the county of Hillsborough and State of Florida, have invented a new, original, and ornamental Design for a Head for Canes and Similar Articles, of which the following is a specification, reference being had to the accompanying drawing, forming a part thereof.

Figure 1 is a front elevation of a head for canes and similar articles, showing my new design.

Figure 2 is a rear elevation of the same.

Figure 3 is a right-hand side elevation of the same.

Figure 4 is a left-hand side elevation of the same.

I claim:

The ornamental design for a head for canes and similar articles, as shown.

WILLIAM D. ADAMS.
